UNITED STATES PATENT OFFICE

2,187,133

EXTENSION TABLE

Valentine C. Luppert, Williamsport, Pa.

Application April 9, 1938, Serial No. 201,170

1 Claim. (CL. 311—56)

This invention relates to improvements in extension tables of the refectory type.

The primary purpose of the present invention is to provide improved means for supporting the extension leaf or leaves of such tables including adjustment means for leveling the leaf or leaves. Another object is to furnish an extension table of simple, inexpensive and sturdy construction, in which the extension leaf supporting means will function effectively without liability of getting out of order.

Another object is to supply an extension table of the refectory type having simple means to eliminate any possible chance of the lid or leaf moving out of place until a bolt is released.

A still further object is to provide improved hardware readily applicable to known types of refectory tables to improve the manipulation, support and leveling of the extension leaves.

With the foregoing objects outlined and with other objects in view which will appear as the description proceeds, the invention consists in the novel features hereinafter described in detail, illustrated in the accompanying drawings, and more particularly pointed out in the appended claim.

In the drawings:

Fig. 1 is a bottom plan view of the top of a refectory type extension table provided with one form of my improvements and showing the movable leaves in extended position.

Fig. 2 is a similar view with the extension leaves contracted.

Figs. 3 and 4 are vertical sectional views taken respectively on the lines 3—3 and 4—4 of Figs. 1 and 2.

Fig. 5 is a side elevation of a corner of a refectory table in accordance with my invention.

Fig. 6 is a part sectional and part elevational view of a detail of a modification of the invention.

Fig. 7 is an enlarged view of a detail of the structure shown in Fig. 3.

Fig. 8 is a view similar to Fig. 7 of the hook portion of the connecting means and showing the hook connected to a wood rail or stretcher.

Referring to the drawings, 8 designates a stationary table top mounted on any suitable support, such as legs 9.

The stationary top includes conventional side bars 10 and end bars 11, the latter being provided with suitable notches or slots 12 (Fig. 7) to accommodate pairs 13 and 14 of inwardly and outwardly movable rails. Each pair of rails supports an extension leaf 15. The rails may be made of any suitable material, and for the sake

of disclosure, I have shown each rail as made of an angle iron strip having a horizontal wing 16 (Fig. 7) from which depends a vertical wing 17. The outer end portion of each rail is secured to one of the extension leaves by any suitable means such as screws 18 (Fig. 1), and the inner end portion of each rail is arranged at a lower elevation than the outer end portion and connected to the latter by a cam portion 19. The cam portions cooperate with the end bars 11 of the table to raise the leaves 15 into a plane parallel with the plane of the stationary top 8, when the leaves are pulled outwardly, and to lower the leaves when the latter are moved inwardly toward one another.

The rails are not only guided by the end bars 11 but also by a stationary cross bar 20 of the table top, which has guide slots 21 to accommodate the inner end portions of the rails.

Each end bar is provided on its inner side with a pair of stationary brackets 22 each having a horizontal cross pin 23. The pins cooperate with supporting hooks 24, each of which has a threaded shank 25 extending through a horizontal wing 16 of a rail, and adjustably secured to the latter by a pair of nuts 26 and 27, arranged respectively above and below such wing. It will be obvious that this construction permits any one of the hooks to be adjusted vertically for the purpose of leveling the extension leaf with which it is operatively connected, and of course, after adjustment, the nuts 26 and 27 may be employed to fixedly lock the hook in position.

Instead of connecting the hooks 24 to the rails, it is obvious that pins 23 might be connected to the rails and the hooks attached either to the stationary table top 8a (Fig. 6) or to the end bars 11. By way of explanation, it is obvious that brackets 22 might be secured to suitable portions of extension elements of the table and each hook 24a could be adjustably secured to a fixed bracket 28.

If wood rails or stretchers 13a (Fig. 8) are used instead of metal rails, each hook 24b may have a threaded shank 24c that is screwed into the bottom of the rail and locked in position by a nut 24d.

I prefer to provide the shanks of the hooks in all cases with sixteen threads to the inch as this will enable the operator to make fine adjustments.

In order to prevent the leaves from accidentally moving upwardly while they are extended, any suitable latching means is provided. For example, each extension leaf may be pro-

vided with a latching member 29 having a spring-projected bolt 30. Each bolt, as shown in Figs. 1 and 2, has a finger hole 31, and of course, when the bolt is released the leaf can be manipulated so as to permit the hooks 24 to be disconnected from the pins 23, and then the leaves may be lowered and pushed inwardly to return them to the position shown in Figs. 2 and 4.

Stationary cross strips 32 to prevent warping 10 of the top are arranged at the bottom of the stationary top 8 between the cross bar 20 and the end bars 11.

In operation, assuming that the parts are in the position shown in Figs. 2 and 4, it will be 15 obvious that if the leaves 15 are pulled outwardly and then lifted, the hooks 24 may be placed in engagement with the pins 23, and then when the leaves are lowered into alignment with the stationary top 8, the ends of the hooks will come to 20 rest on the pins to prevent further downward movement of the leaves. Then the bolts 30 are projected so as to prevent further accidental upward movement of such leaves.

In order to return the leaves 15 to stored position beneath the top 8, the bolts 30 are first 25 released, and then the leaves are manipulated to disengage the hooks 24 from the pins 23, after which the leaves may be slid inwardly while guided by the rails 13, 14.

30 While I have disclosed what I now consider to

be preferred embodiments of the invention, in such manner that the same may be readily understood, I am aware that changes may be made in the specific details disclosed, without departing from the spirit of the invention as expressed in 5 the claim.

What I claim and desire to secure by Letters Patent is:

An extension table comprising a stationary top, 10 an extension leaf, a pair of angle iron rail members slidably supported by the stationary top and supporting the extension leaf, each rail having parallel end portions and a medial cam portion, said cam portion being adapted to cooperate with a portion of the stationary top for elevating the 15 extension leaf into the plane of the upper surface of said top when the leaf is pulled outwardly in a direction away from the stationary top, hooks having threaded shanks adjustably connected to the rails inwardly of the cam portions of the 20 latter, cross pins secured to the stationary top and engageable by the hooks for holding the extension leaf in raised position, and a rigid bolt slidably connected to the bottom of the extension leaf and adapted to be projected under a portion 25 of the table top to prevent the leaf from being moved upwardly after the hooks have been brought into engagement with said pins.

VALENTINE C. LUPPERT. 30
